UNITED STATES PATENT OFFICE.

WILLIAM H. ROBBINS, OF SPRINGFIELD, OHIO, ASSIGNOR TO THE WILLIAMS COMPANY, OF LONDON, OHIO, A CORPORATION OF OHIO.

STEEL-WOOL MACHINE.

Application filed June 5, 1925. Serial No. 35,155.

My invention relates to steel wool machines and in particular to means for conveying away the strands of steel wool therefrom.

5 It is the object of my invention to provide means for engaging the delicate steel wool strands and for moving them at a predetermined desired speed away from the steel wool machine as they are manufactured in 10 such a way as to move them positively without injuring the strands.

It is a further object of my invention to provide means of engaging with the strands so as not to break them but to still frictionally engage them in such a way that the pull 15 on the strands to remove them from the machine will be uniform, constant and steady so that the strands will not be broken.

Referring to the drawings:

20 Figure 1 is a side elevation of one form of the steel wool removing apparatus of my invention located adjacent to a diagrammatic illustration of a typical steel wool machine;

Figure 2 is a plan view of one end of the 25 removing means shown in Figure 1;

Figure 3 is a section on the line 3—3 of Figure 1 showing the supporting bracket broken away and the supporting shafts in section with a strand of steel wool passing 30 between the steel wool actuating members;

Figure 4 is a similar view on the line 4—4 of Figure 5 showing a modified form of the steel wool removing means;

Figure 5 is a plan view of a modified form 35 of this removing means consisting of spaced rods;

Figure 6 is an end elevation of another form of steel wool removing means using solid rolls which frictionally engage with the 40 steel wool strands passing between them;

Figure 7 is a plan view of this modified form illustrated.

Referring to the drawings in detail, 1—1 are standards for supporting the steel wool 45 machine table 2 on either end of which is mounted the supporting brackets consisting of the upright members 3 which terminate in spaced members 4, thus forming Y-shaped brackets at either end of the machine. It

50 will be understood that this steel wool removing means may be located anywhere, that is, above, below or at one side of the steel wool machine but for the purpose of illustration and the ease thereof, I have shown 55 it in a typical satisfactory form above the

machine. Journaled in the ends of these arms 4 of the Y-shaped bracket are the shafts 5 and 6 which are thus supported in parallel relationship. On one of these shafts is mounted a pulley 7 actuated by a belt 8 from any suitable source of power. These shafts have mounted thereon, opposite to one another, the gears 9 and 10 which mesh with one another and serve to turn the shafts 5 and 6 in unison with one another so that there will be synchronous movement of the shafts and any means which they may carry. The shafts carry, on suitable end supporting members or plates 11 corrugated drums 12, such corrugations being formed as round topped ridges 13 which are relatively widely spaced with deep valleys 14 therebetween. These two corrugated drums have their projecting corrugations or ridges 13 adapted to project within the corresponding valleys 14 on the other corrugated drum but the drums are so positioned through the gearing 9 and 10 that while successive ridges project into opposite successive valleys, yet the drums do not touch each other but are spaced a sufficient distance 75 between their adjacent surfaces to accommodate the steel wool strands 15 passing from the steel wool cutting tools 16. These strands are fed between the corrugated rolls and are bent in serpentine form as they pass between the corrugations of the rolls where the corrugations of the rolls are adjacent, thus providing a frictional engagement for moving the strands. The strands are therefore moved by this engagement at a 80 predetermined speed without jerking or pulling and without rupture of the strands but they are nevertheless positively moved. The strands are easily examined as they are thus moved from the machine enabling the operator to make the adjustments on the cutting tools as may be desired.

These strands are cut from the wire 17 passed over the drums 18 in the usual manner. These drums are mounted on the table 100 2 on the vertical spindles 19. It will be understood, however, that the details of the steel wool machine are immaterial as one or more wires may be used and other details of the machine may be modified. The drums shown in Figures 1, 2 and 3 are preferably formed of corrugated sheet metal. In Figure 4 an open type of removing mechanism is illustrated where it is desired to have this form which provides for a circulation of 110.

air. The mechanism is the same with the exception that instead of having actuating drums with continuous faces, rods 20 are provided mounted on the crests of the teeth 5 21 of the end members 22. The wall engages with these rods which loosely interlock as in the case of the forms shown in Figures 1, 2 and 3, not touching each other and being sufficiently spaced to accomodate the steel 10 wool strand which is frictionally engaged by the rods and moved away from the tools.

Referring to the form shown in Figures 6 and 7, it will be observed that the mechanism is the same save that two solid, 15 smooth-faced rolls 23 are employed which are sufficiently spaced to a minute degree not to engage one another but to insure frictional engagement with the fine strands of wool which pass therebetween.

20 It will be understood that I desire to comprehend within my invention such modifications as may be necessary to adapt it to varying conditions.

Having thus fully described my invention, 25 what I claim as new and desire to secure by Letters Patent, is:—

1. In a steel wool machine, cutters for said steel wool machine, means for feeding a wire to said cutters whereby a plurality 30 of individual strands of steel wool are cut simultaneously by said cutters from said wire, means to remove steel wool strands from the cutters consisting of a pair of synchronously moving, closely adjacent steel 35 wool engaging members adapted to frictionally engage the wool strands individually to pull them away from the cutters, said friction engaging members having means for grasping said steel wool strands where- 40 by only the dead weight of the wool strands is lifted by said friction engaging members without tension.

2. In a steel wool machine, cutters for said steel wool machine, means for feeding 45 a wire to said cutters whereby a plurality of individual strands of steel wool are cut simultaneously by said cutters from said wire, means to remove steel wool strands from the cutters consisting of a pair of 50 synchronously moving, closely adjacent steel wool engaging members adapted to frictionally engage the wool strands to pull them away from the machine, said members being adapted to move together synchronously but 55 not to engage one another and only adapted to very lightly frictionally engage with the individual steel wool strands passing there- 60 between whereby only the dead weight of the wool strands is supported by said mem- bers without tension.

3. In a steel wool machine, cutters for said steel wool machine and means for feed- 65 ing wire to said cutters whereby a plurality of strands of wire are cut simultaneously, means to remove steel wool strands from the

cutters consisting of a pair of synchronously moving, closely adjacent steel wool engag- 70 ing members adapted to frictionally engage the wool strands to pull them away from the machine, said members being adapted to move together synchronously but not to engage one another and only adapted to frictionally engage with the steel wool strands passing therebetween, and said members being furthermore so arranged with alternate 75 projections and depressions on said mem- bers, the projections of one member adapted to project into the depression of the other member without engaging with the member and the strands being adapted to pass 80 between the alternate projections and de- pressions in the members where they are adjacent to one another, thus frictional bends being formed in the steel wool strands to assist in pulling the strands away from the 85 machine.

4. In a steel wool machine, cutters for said steel wool machine, means for feeding a wire to said cutters whereby a plurality 90 of strands of wire are cut simultaneously by said cutters, means for removing the strands from said cutters, consisting of a pair of synchronously rotating corrugated drums adapted to have the corrugations suc- 95 cessively interlocked but never engaged and being sufficiently spaced to permit of the passage of steel wool strands therebetween for very light frictional engagement with said drums sufficient to move a strand of steel wool to carry its dead weight but not 100 to put it under tension whereby only the dead weight of the wool strands is sup- 105 ported and lifted by said steel wool engag- ing members.

5. In a steel wool machine, cutters for 105 said steel wool machine, means for feeding a wire to said cutters whereby a plurality 110 of individual strands of steel wool are cut simultaneously by said cutters from said wire, means for moving steel wool strands away from the cutters consisting of parallel shafts, gearing mounted on said shafts to insure their rotation synchronously, means for actuating said shafts, and cor- 115 rugated drums mounted on said shafts adapted to interlock without touching being sufficiently spaced for steel wool strands to pass therebetween in frictional engagement with said drums, said frictional engagement being only sufficient to move the strands of 120 wool away from the machine without pull- 125 ing the strands and putting them under ten- sion.

6. In a steel wool machine, cutters for 125 said steel wool machine, means for feeding a wire to said cutters whereby a plurality 130 of individual strands of steel wool are cut simultaneously by said cutters from said wire, means for moving steel wool strands away from the cutters consisting of par-

allel shafts, gearing mounted on said shafts to insure their rotation synchronously, means for actuating said shafts, and corrugated drums mounted on said shafts adapted to 5 interlock without touching being sufficiently spaced for steel wool strands to pass there-between in frictional engagement with said drums, said drums being located above and spaced from the wire from which said 10 strands are being taken, said frictional en-

gagement of the wool strands with the drums being only sufficient to elevate the strands without putting them under tension or pulling them individually whereby only the dead weight of the strands is supported by 15 said drums without tension.

In testimony whereof, I affix my signature.

WILLIAM H. ROBBINS.
